(57) **CLAIM**

The ornamental design for a carry assist device, as shown and described.

DESCRIPTION

FIG. 1 is a perspective view of a carry assist device of the present design;

FIG. 2 is a front view of the present design;

FIG. 3 is a rear view of the present design;

FIG. 4 is a left side view of the present design;

FIG. 5 is a right side view of the present design;

FIG. 6 is a top view of the present design; and,

FIG. 7 is a schematic drawing showing the carry assist device of the present invention in an alternate position.
